CLOSED AND OPEN FIRE CONTROL MECHANISM

Clarence E. Simpson, Wilbraham, Mass., assignor to the United States of America as represented by the Secretary of the Army

Application July 11, 1956, Serial No. 597,310

5 Claims. (Cl. 89—140)

(Granted under Title 35, U. S. Code (1952), sec. 266)

The invention described herein may be manufactured and used by or for the Government for governmental purposes without the payment of any royalty thereon.

This invention relates to fire control mechanisms for firearms.

With the wide variety of conditions under which light firearms are used in modern warfare, it is important that they be adaptable to as many conditions as possible without requiring any major structural alterations.

It is, therefore, an object of this invention to provide for light firearms a fire control mechanism which may be easily switched between automatic and semiautomatic fire.

It is another object of this invention to provide for light firearms a fire control mechanism which has the advantages of firing from a closed bolt position during semiautomatic fire, for precision shooting, and from an open bolt position during automatic fire to reduce the danger of "cook-off" when the firearm is stopped in a closed bolt position after a burst of automatic fire.

It is a further object of this invention to provide for a light firearm a fire control mechanism which may be operated by a conventional trigger means positioned at the forward end of the receiver or by a trigger means at the rear of the receiver when the conventional trigger is not accessible because of mounting conditions as when mounted on a bipod or a tripod.

It is a still further object of this invention to provide for light firearms a fire control mechanism having a pistol grip with conventional trigger mechanism for shoulder fire which is readily removed from the gun when hindering the mounting thereof.

It is another and still further object of this invention to provide a fire control mechanism wherein the automatic sear acts as a safety to prevent the operation of the firing mechanism until the bolt is locked in battery position.

The specific nature of the invention as well as other objects and advantages thereof will clearly appear from a description of a preferred embodiment as shown in the accompanying drawings in which:

Fig. 1 is a partially cross-sectioned elevational view showing the fire control mechanism regulated to fire semiautomatically from closed bolt position by the trigger and the bolt in battery position but not locked therein by the locking sleeve;

Fig. 2 is a view taken along line 2—2 of Fig. 1;

Fig. 3 is a view similar to Fig. 1 but shows the sear disconnected from the trigger by the selector;

Fig. 4 is a view similar to Fig. 2 but shows the arrangement of the parts when the bolt is locked in battery position;

Fig. 5 is a view taken along line 5—5 of Fig. 4;

Fig. 6 is a view similar to Fig. 1 but shows the fire control mechanism regulated to fire automatically from open bolt position with trigger control and the bolt releasably held in recoil position;

2

Fig. 7 is a view similar to Fig. 6 but showing the bolt released and in battery position;

Fig. 8 is a view similar to Fig. 1 but showing the fire control mechanism regulated to fire automatically from a closed bolt position and the bolt in battery position;

Fig. 9 is a view similar to Fig. 8 but showing the firing pin actuated by the hammer;

Fig. 10 is a partially cross-sectioned elevational view of the receiver with the pistol grip assembly removed and the fire control mechanism regulated to fire automatically from open bolt position and the bolt releasably held in recoil position;

Fig. 11 is a view similar to Fig. 10 but showing the bolt release actuated to release the bolt; and

Fig. 12 is an enlarged exploded view of the hammer and secondary sear mechanisms.

Shown in the figures is a light firearm having a tubular receiver 12 which is terminated at the rear end by a shoulder fitting butt section to form the stock of the firearm. A barrel 16 is mounted to the front end of receiver 12 and a hollow, open-top pistol grip housing 18, which assists in manually supporting and aiming the firearm, is detachably mounted to the bottom side of such receiver by means of a conventional slot and tongue device at the front and a catch at the rear end of such housing. A longitudinal slot 19 provides communication between the interior of receiver 12 and the interior of pistol grip housing 18. A bolt 20 is slidably mounted within receiver 12 and is actuatable to a recoil position along the longitudinal axis of such receiver by a conventional gas-operated device (not shown). Bolt 20 is biased to a battery position by suitable spring means and is locked in battery position by a locking sleeve 26 which is rotatable to an unlock position by the gas-operated device and to a lock position by such device when such bolt is in battery position. Slidably mounted through bolt 20 is a firing pin 28 having a cartridge striker portion 30 and an extension portion 32 which protrudes from the rear end of such bolt.

Provided in the rear portion of receiver 12 is a recoil buffer assembly 34 which absorbs the recoil forces in bolt 20 when in recoil position and which includes a plunger 36 engageable by such bolt, a spring 38 for resisting rearward movement of such plunger, and a cylindrical housing 40 for such plunger and spring. Extending through the front end of plunger 36 for a purpose to be described hereinafter is a vertical slot 41.

Extending forwardly from the front end of housing 40 and along the lower inside portion of receiver 12 is a pair of laterally-spaced ribs 42 which are fixed to the inside of such receiver as by welding and which extend vertically upward to form a trough 44 therebetween. The front ends of ways 42 are terminated by inwardly facing lip portions 46 which are located at a position which is rearwardly of the rear end of bolt 20 when in battery position. Placed in trough 44 is a hammer assembly 48 which lies below the path of bolt 20. Hammer assembly 48 is provided with a rectangular housing 50 which is substantially the same width as trough 44 so as to be restrained against lateral displacement. The front end of buffer assembly housing 40 and lip portions 46 restrain hammer assembly 48 against longitudinal displacement. Sufficient longitudinal space is provided, though, to permit the rear end of hammer assembly 48 to be pivoted upwardly.

Extending rearwardly into housing 50 from the front end thereof is a longitudinal opening 51 comprised of a rearward bore portion 52, which is terminated by a wall 54, and a T-slot 55 extending forwardly therefrom. The front end of housing 50 is bifurcated by a vertical slot 56 and the front of the tine portions 58 formed by such slot have respective engagement with lip portions 46.

The ends of tine portions 58 are arcuately formed in the vertical plane so as to reduce the area of engagement between such tine portions and lip portions 46 as the rear end of housing 50 is raised and lowered. A carrier 60 of T-configuration is slidably mounted in T-slot 55 and such carrier is bifurcated at the front end by a slot 62, which is similar in width to slot 56, to form a bifurcated portion 64. Received by opening 51 is a cylindrical plunger 66 having a central portion 68 which has sliding engagement with the surface of bore 52 and a rearwardly extending rod portion 70 of smaller diameter. Provided in bore 52 is a compressible coil spring 72 which engages wall 54 at one end and receives rod portion 70 at the opposite end to engage the adjacent side of central portion 68 so as to bias such plunger forwardly. Another rod portion 74 extends forwardly from central portion 68 to be slidably received by an axial aperture 76 through carrier 60. Rod portion 74 is slightly longer than carrier 60 and is terminated by a diametrically disposed face 78. A pin 80 is rotatably received by a pair of laterally disposed holes 82 in bifurcated portions 64, and the ends of such pin extend beyond carrier 60 to be received by a pair of elongated longitudinally disposed slots 84 in housing 50 to limit the movement of such sleeve therein. Mounted on pin 80 in slot 62, as by press fit, so as to secure such pin against lateral displacement is a hammer 86 which is flat in configuration and of substantially the same width as slots 56 and 62. Hammer 86 is provided with a body portion 88 having a hole 90 therethrough to receive pin 80. An arm portion 92 extends upwardly and forwardly from body portion 88 to be engageable with extension portion 32 of firing pin 28 for actuation thereof to fire a cartridge chambered in barrel 16.

The top side of arm portion 92 inclines upwardly and forwardly and is cammingly engageable with the rear side of slot 56 so that such arm is moved downwardly to be received by T-slot 55 as carrier 60 is retracted within housing 50 to a cock position. Provided on the rear side of body portion 88 is a flat 94 which, when fully engaged with face 78, resiliently holds arm portion 92 upwardly in position to engage firing pin 28, and a projecting ledge 95 on the top side of flat 94 is engageable with rod 74 to secure hammer 86 against rearward rotation when firing pin 28 is struck thereby.

Extending rearwardly into housing 40 from the front end thereof is a triangularlike, vertically disposed recess 96 which is provided with a top side 98 that inclines rearwardly and downwardly from the front end of such housing and which is arranged to receive a tongue 100 which extends rearwardly from the rear end of hammer housing 50. The top side of tongue 100 is inclined to mate with side 98 and to cooperate therewith to provide limited vertical movement of the rear end of such hammer housing. A flat spring 102 is mounted in recess 96 to engage the bottom side of tongue 100 and bias hammer assembly 48 upwardly until such tongue engages top side 98 of recess 96.

A rectangular bar 104 is mounted for longitudinal, non-rotating movement through a pair of longitudinal bosses 106 fixed to the inside of receiver 12 on the left side thereof. The front of bar 104 is terminated by a face 108 which has sliding engagement with the rear end of locking sleeve 26 away from the axis thereof. The rear end of bar 104 is terminated adjacent sleeve 60 by a mounting portion 110 which protrudes outwardly into a bay 112 extending from receiver 12. Extending laterally through mounting portion 110 is an elongated opening 114 which is transversed by a vertical pin 115 adjacent the front end of such opening and in alignment with the outside surface of bar 104.

A sear member, hereinafter referred to as secondary sear 116, is mounted for pivotal movement on pin 115 and includes an arm portion 118 which is extendable through an elongated slot 120 in housing 50 for releas-

able engagement with catch portion 122 in carrier 60. Inward movement of arm portion 118 beyond engaging position is prevented by the engagement of a flat 124 on the front portion of secondary sear 116, inward of pin 115, with the front end of such flat. Secondary sear 116 is biased to engaging position by a flat spring 126 which is mounted to the inside surface of the adjacent one of the ribs 42 forwardly of bay portion 112 and is arranged to resiliently engage the outside surface of arm portion 118. When secondary sear 116 is in engaging position and face 108 is engaged with the rear face of locking sleeve 26, the front end of slot 120 is engaged with the rearwardly and inwardly extending inside surface of such arm portion noted at 127.

Provided in the rear side of locking sleeve 26 and in alignment with bar 104 is a notch 128 which permits bar 104 to be moved forwardly by the bias of coil spring 72 which is transferred to such bar by the engagement of arm portion 118 with catch portion 122. However, during such forward movement of bar 104, secondary sear 116 carried thereby is cammed out of engagement with catch portion 122 by the sliding engagement of the front portion of slot 120 with the inside surface 127 of arm portion 118. Cam portions 129 and 130 on the front end of bar 104 and on one side of notch 128, respectively, cooperate to move such bar out of such notch during rotation of locking sleeve 26 to unlock bolt 20.

Provided in the front end of piston grip assembly 18 is a trigger guard portion 131 which forms an opening 132. Extending transversely through piston grip assembly 18 above opening 132 is a pin 134 and pivotally mounted thereon is a trigger 136 having a body portion 138 provided with a hole 140 through the front end thereof to receive pin 134. A finger piece 142 depends from the rear of body portion 138 into opening 132. Provided in the top rear portion of body portion 138 is a recess 144 having a substantially vertical front side 146 and a bottom side 148 which extends rearwardly therefrom at an angle which is slightly more than 90°. A pin 150 extends laterally through body portion 138 so as to pass through the front side of recess 144. Pivotally mounted on pin 150 is a disconnector 152. Such disconnector is provided with a leg portion 154, which extends upwardly into receiver 12 through slot 19, and a foot portion 156 which extends rearwardly therefrom at an angle of approximately 90°. Pin 150 is mounted transversely through disconnector 152 at the junction of leg portion 154 and foot portion 156. As the angular relationship of front side 146 and bottom side 148 is slightly more than 90°, and that of leg portion 154 and foot portion 156 is approximately 90°, such disconnector is pivoted between engagement of such leg portion with such front side and engagement of such foot portion with such bottom side. Extending downwardly into body portion 138 is a bore 160 and received therein is a plunger 162 which is spring-biased against the bottom side of foot portion 156 to pivot leg portion 154 forwardly by a spring 164.

Extending transversely through the top of pistol grip assembly 18, adjacent the front end of housing 50, is a pin 166 which provides a pivotal mount for a substantially linear sear 170. Sear 170 is provided with an engaging portion 172, which extends rearwardly from pin 166 to be engageable with a catch portion 174 in the bottom side of carrier 60 to releasably hold hammer 86 in a cock position slightly rearward of the automatic cock position held thereby by secondary sear 116, and an actuator portion 176 which extends forwardly along slot 19. Provided in actuator portion 176 is a vertical slot 178 which receives therethrough leg portion 154 of disconnector 152 and permits limited pivotal movement thereof. A coil spring 179 resiliently rotates sear 170 to move engaging portions 172 upwardly in position to engage catch portion 174.

The top front portion of leg portion 154 is cut away, as noted at 180, to form a ledge 182 at the bottom side and such ledge is engageable with the bottom side of actuator portion 176, forward of vertical slot 178, when disconnector 152 is in normal forward position. Whereby, when finger piece 142 is pulled rearwardly, disconnector 152 is moved upwardly, by being mounted rearwardly of the pivotal point of trigger 136, and with ledge 182 being in engagement with the inner side of the forward actuator portion 176, such actuator portion is moved upwardly to pivot engaging portion 172 downwardly out of engagement with catch portion 174 to release hammer 86. A cam surface 184 extends upwardly and rearwardly from the rear side of cutaway portion 180 for a purpose to be hereinafter explained.

Mounted transversely through receiver 12 above trigger 136, so as to cooperate with disconnector 152 as hereinafter described, is a selector 186. Selector 186 includes a rod portion 188, which is rotatably mounted transversely through receiver 12 by means of suitable holes therethrough, and a suitable handle means is fixed to one end of such rod and is located on the outside of such receiver. Selector 186 is so disposed in cooperation with disconnector 152 that when such disconnector is moved upwardly by finger piece 142, cam surface 184 cammingly engages the perimeter of rod portion 188 to pivot leg portion 154 rearwardly and so move ledge 182 out of engagement with actuator portion 176 and permit spring 179 to rotate sear 170 into position to reengage such catch portion during the next cycle of operation. However, a segmental portion 191 is cut out of rod portion 188 so that when selector 186 is rotated to move such segmental portion adjacent leg portion 154, cam surface 184 is not engageable with such rod portion to cam such leg portion rearwardly. Therefore, ledge 182 remains in engagement with sear 170 and engaging portion 172 held down out of engagement with catch portion 174 so long as finger piece 142 is held rearwardly.

A pin 192 extends laterally through piston grip housing 18 rearwardly of sear 170 and provides an axle for a trip lever 194 pivotally mounted thereon. Trip lever 194 includes a front portion 196 having a front end which has engagement with bottom side 148 of recess 144, and a rear portion 198 the end of which is received by a hook portion 200 which depends from the bottom of housing 50. Whereby, when finger piece 142 is pulled rearwardly, bottom side 148 is moved upwardly to pivot rear portion 198 downwardly moving with it against the bias of spring 102 the rear end of housing 50.

Projecting upwardly from the rear of the top side of housing 50 is a divided lug 202 which is engageable with a stop portion 204 on the rear end of bolt 20 for holding such bolt in the recoil position when the rear end thereof is in a normal upward position and is disengaged therefrom when rear portion 198 of trip lever 194 pulls such rear end downwardly through a rearward pull on finger piece 142. A cam surface 205 on the front end of lug portion 202 provides the means for depressing such lug portion out of the way during recoil flight of bolt 12. The rear end of housing 50 may also be moved downwardly to disengage lug 202 from stop portion 204 by a bolt release 206 which is mounted for slideable vertical movement through a hole 208 provided in a mounting portion 210 extending forwardly from the top front side of housing 40 and through slot 41 in plunger 36 to engage the top side of housing 50. A lock 212 is slidably mounted on the outside of receiver 12 for cooperation with bolt release 206 to selectively lock such bolt release in a down position whereby the rear end of housing 50 is held downwardly so that stop portion 204 is not engageable by lug 202.

Operation

When the firearm is to be fired automatically from open bolt position and through the control of finger piece 142,

selector 186 is turned to rotate rod portion 188 so that segmental portion 191 is adjacent leg portion 154 of disconnector 152 and the rear end of housing 50 is released from depressed position by unlocking lock 212 whereby spring 102 biases such rear end upwardly. With the rear end of housing 50 in elevated position, hook 200 raises rear portion 198 of trip lever 194 and lowers front portion 196 into engagement with bottom side 148 of recess 144.

10 Bolt 20 is then retracted by charging means (not shown) until stop portion 204 thereon is engaged by lug portion 202 on housing 50 to releasably hold such bolt in the recoil position. When bolt 20 is retracted to the recoil position, the end of hammer 86 is engaged

15 by the rear end of bolt 20 after which continued rearward movement of such bolt causes arm portion 92 of such hammer to be cammed downwardly and rearwardly by engagement of the top side of such arm portion with the rear side of slot 56 into T-slot 55 to press carrier 60 against coil spring 72 to permit bolt 20 to pass by. Hammer 86 is held within T-slot 55 by the engagement of secondary sear 116 with catch portion 122 and arm portion 92 held downwardly by the sliding engagement of the end thereof with the bottom side of bolt 20.

20 25 When the firearm is to be fired, finger piece 142 is pulled rearwardly whereby bottom side 148 of recess 144 is pivoted upwardly carrying with it front portion 196 of trip lever 194. Consequently, rear portion 198 is pivoted downwardly depressing the rear end of housing

30 30 35 50 to release stop portion 204 from lug 202. Whereupon, bolt 20 is released to be biased to battery position by suitable spring means, which were energized by such bolt during flight to recoil position, and during such forward movement a cartridge is picked up from a feeding mechanism (not shown) and chambered in barrel 16.

35 After the rear end of bolt 20 passes over hammer 86 in going to battery position, arm portion 92 is freed to be biased upwardly into position to actuate firing pin 28. However, hammer 86 is prevented from striking firing pin 28 because of the engagement of secondary sear 116 with catch portion 122 in carrier 60, which slidably carries such hammer, as sear 170, which would have engaged such sear before such secondary sear, is pivoted out of the way by the upward position of disconnector 152 while finger piece 142 is held rearwardly.

40 45 50 Until bolt 20 is in battery position and is locked therein by rotation of locking sleeve 26, hammer 86 remains cocked by secondary sear 116. However, when locking sleeve 26 is rotated so that bolt 20 is fully locked, notch 128 is aligned with bar 104. Therefore, bar 104 and secondary sear 116 are moved forwardly by the bias of coil spring 72 transferred thereto by the engagement of arm portion 118 with catch portion 122 and during such forward movement arm portion 118 is cammed out 55 of engagement with catch portion 122, freeing carrier 60 which moves hammer 86 forwardly to strike firing pin 28 and fire the chambered cartridge.

55 60 65 With the ensuing recoil of bolt 20, the same action takes place as previously described for the charging operation and the firing cycle continues until finger piece 142 is permitted to return to normal forward position. Whereupon, spring 102 biases the rear end of housing 50 upwardly in position for lug 202 thereon to engage stop portion 204 on bolt 20 to stop the firing cycle and releasably hold such bolt ready to fire another cartridge when finger piece 142 is actuated again.

70 75 When the firearm is to be fired automatically from closed bolt position and with trigger control, bolt release 206 is pushed downwardly to depress the rear end of housing 50 so that lug 202 thereon will not be engageable with stop portion 204 and then locked in down position by lock 212. With the rear end of housing 50 in down position, front portion 196 of trip lever 194 is pivoted out of engagement with trigger 136 and so will not be actuatable thereby. Selector 186 is posi-

tioned so that segmental portion 191 is adjacent leg portion 154 of disconnector 152.

The firearm is charged by manually actuating bolt 20 to recoil position and then returned to battery position to pick up and chamber a cartridge from the feeding mechanism (not shown). During recoil travel of bolt 20, hammer 86 is retracted into T-slot 55, as hereinbefore disclosed, to be releasably engaged by sear 170 to cock such hammer. Thus, when finger piece 142 is pulled rearwardly to fire the firearm, disconnector 152 is moved upwardly against actuator portion 176 of sear 170 to pivot engaging portion 172 downwardly to release carrier 60 which, through the bias of the loaded coil spring 172, moves hammer 86 forwardly to strike firing pin 28 for firing the chambered cartridge. As bolt 20 finished in a locked battery position when the charging was completed, secondary sear 116 was automatically biased to the disengaged position, as hereinbefore described, and so out of position to intercept movement of hammer 86.

During the resulting recoil of bolt 20, hammer 86 is retracted, as hereinbefore described, and so long as finger piece 142 is held rearwardly for continued fire and sear 170 is, consequently, held out of engagement with carrier 60. Such carrier will be cyclicly engaged during movement of such bolt to battery position by secondary sear 116 and automatically released therefrom when bolt 20 is locked in battery position. Firing will continue until the ammunition is depleted or finger piece 142 is released to return to normal position. Whereupon, sear 170 is positioned to engage carrier 60 before secondary sear 116 and thereby stop the firing and releasably hold hammer 86 ready to resume firing when finger piece 142 is again retracted.

To fire the firearm semiautomatically from closed bolt position and with trigger control, selector 186 is rotated so that the perimeter of rod portion 188 will be engageable by cam surface 184 on leg portion 154. Therefore, with the firearm charged and hammer 86 cocked by sear 170, a rearward pull on finger piece 142 causes disconnector 152 to be pivoted upwardly to actuate sear 170 for releasing hammer 86 to fire the chambered cartridge. However, during upward movement of leg portion 154, cam surface 184 thereon engages rod portion 188 to cam such leg portion rearwardly and thereby disengages ledge 182 from sear 170 after such sear is actuated to release hammer 86. After being released from disconnector 152, sear 170 is biased by coil spring 179 so that engaging portion 172 is in position to engage catch portion 174 of carrier 60 and cock hammer 86. To fire another cartridge, finger piece 142 will have to be retracted again, and it is obvious that the operator will not be able to fire the firearm until bolt 20 is in locked battery position as secondary sear 116 will remain in position to engage carrier 60 and stop hammer 86, after being released from sear 170, until locking sleeve 26 is in full locked position. Then, as hereinbefore described, secondary sear 116 will release hammer 86 automatically to fire the chambered cartridge. It is obvious, therefore, that secondary sear 116 also acts as a safety as it prevents the firing of a cartridge until bolt 20 is locked in battery position.

When the mounting of the firearm makes it impossible or difficult for the operator to actuate finger piece 142 or if pistol grip housing 18 is in the way, such pistol grip housing is removed and with it the components mounted therein. Lock 212 is then actuated to release bolt release 206. When bolt release 206 is released, the rear end of housing 50 is released to be biased upwardly by flat spring 102 so that lug 202 on such housing will be engageable with stop portion 204 on bolt 20. Thus, when the firearm is charged, bolt 20 is releasably held in recoil position by housing 50 and the firing of the firearm is controlled by bolt release 206. To fire the firearm, bolt release 206 is pressed downwardly to re-

lease bolt 20 which goes forwardly to battery position and, when locked therein by locking sleeve 26, secondary sear 116 will automatically release hammer 86 to fire the chambered cartridge, as hereinbefore described. To stop firing, pressure is released from bolt release 206 whereby the bias of flat spring 102 elevates the rear end of housing 50 to engage bolt 12 during recoil flight.

The firearm may be fired by bolt release 206 without removing pistol grip housing 18 if provision is made to lock finger piece 142 in a retracted position so as to maintain sear 170 out of bolt engaging position.

From the foregoing, it is clearly apparent that there is herein provided a novel firing mechanism which is readily adapted for many types of operation, which provides a member which is both an automatic sear and a safety to prevent the firing of a cartridge before the bolt is locked in battery position and which is simple and rugged in construction.

Although a particular embodiment of the invention has been described in detail herein, it is evident that many variations may be devised within the spirit and scope thereof and the following claims are intended to include such variations.

I claim:

1. For a firearm provided with a bolt reciprocable between a recoil and a battery position, a sleeve for rotatably locking the bolt in the battery position and a firing pin slidably mounted in the bolt, a fire control mechanism for selectively firing the firearm from open or closed bolt position and for automatic or semiautomatic operation including a hammer biased for engagement with the firing pin and actuated by the bolt to a retracted position during movement of the bolt to the recoil position, a secondary sear device for releasably holding said hammer in the cocked position forwardly of the retracted position and being arranged for cooperation with said hammer for the automatic release thereof when the bolt is locked in battery position, a sear for releasably holding said hammer in the retracted position, a detachable trigger device for actuating said sear to release said hammer when held thereby, pivotal means for releasably holding the bolt in the recoil position for firing the firearm from the open bolt position, lever means actuatable by said trigger device for pivoting said pivotal means to release the bolt and to hold said lever means away from the bolt holding position to effect automatic firing by said secondary sear device, and a bolt release member for pivoting said pivotal means when said trigger device is detached from the firearm to fire the firearm automatically and to hold said lever means away from the bolt holding position to enable semiautomatic firing from closed bolt position through the cooperation of said sear and said trigger device.

2. For a firearm provided with a bolt reciprocable between a recoil and a battery position, a sleeve for releasably locking the bolt in the battery position and a firing pin slidably mounted in the bolt, a fire control mechanism for selectively firing the firearm from a closed or open bolt position and for automatic or semiautomatic operation including a hammer biased for engagement with the firing pin and being retractable by the bolt to a retracted position during movement of the bolt to the recoil position, a secondary sear device cooperable with the locking sleeve for releasably holding said hammer in a cocked position forwardly of the retracted position and with said hammer for the automatic release thereof when the bolt is locked in battery position for automatic operation of the firearm, a sear for releasably engaging said hammer when in the retracted position and the bolt is in the battery position to fire the firearm from closed bolt position and with semiautomatic operation, a detachable trigger device for actuating said sear to release said hammer, pivotal means for releasably holding the bolt in the recoil position to operate the firearm from open bolt position, lever means actuatable

by said trigger device for pivoting said pivotal means to release the bolt and effect automatic fire, a bolt release member for pivoting said pivotal means when said trigger device is detached from the firearm and for holding said pivotal means away from bolt holding position to provide uninterrupted control of said hammer by said sear, and disconnecting means for disconnecting said trigger device from said sear after the release of said hammer by said trigger device and for reconnecting said trigger device to said sear to effect semiautomatic fire.

3. For a firearm provided with a receiver, a bolt slidably mounted in the receiver for reciprocation between a recoil and a battery position, a firing pin slidably mounted in the bolt and a locking sleeve for rotatably locking the bolt in the battery position, a fire control mechanism including means for selectively firing the firearm automatically or semiautomatically and from an open or a closed bolt position comprising a longitudinally disposed hammer housing mounted for pivotal movement in the receiver, spring means for resiliently pivoting said hammer housing to an engaging position, cooperating latching means on said hammer housing and the bolt for releasably holding the bolt in the recoil position when said hammer housing is in the engaging position, a trigger mechanism detachably mounted to the front end of the receiver, lever means actuatable by said trigger mechanism for pivoting said hammer housing out of engagement with the bolt, a manually-operated bolt release slidably mounted to the rear end of the bolt receiver for engagement with said hammer housing for actuation thereof to release the bolt, a hammer member slidably mounted in a longitudinal opening in the front end of said hammer housing for engagement with the firing pin and for actuation by the bolt to a retracted position within said opening during movement of the bolt to recoil position, a spring mounted in said opening for biasing said hammer member against the firing pin when the bolt is in battery position, sear means engageable with said hammer member and actuatable by said trigger mechanism for firing the firearm semiautomatically from a closed bolt position, and secondary sear means actuatable by said hammer member in cooperation with the locking sleeve for automatically releasing said hammer member to automatically fire the firearm from open bolt position when said housing is held out of the engaging position by said trigger mechanism or said bolt release and to prevent the firing of the firearm when selected for semiautomatic operation until the bolt is in locked battery position.

4. The combination of claim 3 wherein said hammer device includes a carrier having a forwardly extending bifurcated portion slidably mounted in said opening, a tine portion at the forward end of said housing formed by a vertical slot, a hammer member pivotally mounted on a pin extending transversely through said bifurcated portion, an arm portion on said hammer extendable through said slot for engagement with the firing pin, plunger means slidably mounted in said opening between said carrier and said spring so as to transmit the bias of said spring to said carrier, a rod portion extending slidably through an axial aperture in said carrier for engagement with said hammer member, a flat on said hammer member cooperable with the engaging end of said rod for biasing said arm portion into a position for engagement with the firing pin, cooperating cam means on said arm portion and said housing for moving said hammer member into said opening when said portion is engaged by the bolt during movement to recoil position, and a ledge portion on said hammer member cooperable with said rod portion for preventing pivotal movement of said hammer member when actuating the firing pin.
5. The combination of claim 3 wherein said secondary sear means includes a bar slidably mounted in the receiver and having one end slidably engaged with the locking sleeve, a sear member pivotally mounted to the opposite end of said bar for releasable engagement with a catch portion in said hammer device when retracted by the bolt to releasably secure said hammer device in a cocked position and transfer the bias of said hammer device to said bar, a notch in the locking sleeve into which said one end of said bar is moved by the bias of said hammer device when the locking sleeve is rotated to lock the bolt in battery position, and cam means for moving said sear member out of engagement with said hammer device during movement of said bar into said notch.
